DOILY DRIER

Filed March 2, 1946

Inventor

15 29
Levina May Kidder

A diagram of a dental arch, likely a maxillary arch, shown in a cross-sectional view. The arch is supported by six dental implants, each with a threaded screw and a dental crown. The implants are labeled with the number 14 on both the left and right ends. Along the arch, there are four numbered points: 38, 39, 36, and 40. Point 37K is also indicated, positioned between points 38 and 39. The arch is supported by a dental bridge or partial denture, which is anchored to the implants. The entire assembly is labeled 'By' at the bottom right.

UNITED STATES PATENT OFFICE

2,519,767

DOILY DRIER

Levina May Kidder, New Castle, Pa.

Application March 2, 1946, Serial No. 651,494

7 Claims. (Cl. 45—24)

1

The invention as described herein, and illustrated in the accompanying drawings, consists of a dryer, an object of which is to provide means whereby knit doilies, mats and the like may be shaped in the drying process thereof.

Another object of the invention is to provide a resilient support upon which doilies may be simultaneously dried and stretched into proper shape.

A further object of this invention is to provide a sectional resilient stretcher for doilies and the like.

Another object of the invention is to provide an adjustable stretcher for doilies and the like.

Another object of the invention is to provide a stretcher comprising a series of fixed and adjustable teeth for engaging knitted mats and the like.

Other features and advantages will become more readily apparent from the following description and the accompanying illustrative drawings in which:

Figure 1 is an elevational view of the dryer, broken away.

Figure 2 is an elevational view shown in operative position,

Figure 3 is a plan view thereof partly broken away.

Figure 4 is an enlarged small broken away part of the device.

Figure 5 is an enlarged detail elevational view of a pin,

Figure 6 is an edge view of Figure 4,

Figure 7 is a detail edge view of broken away part of the device,

Figure 8 is a detail elevational view of an adjustment member,

Figure 9 is an elevational view of a modification,

Figure 10 is an enlarged detail elevational view illustrating a support, and

Figure 11 is a top plan view of the hoop formed into a square shape by use of a pair of elongated members.

While one embodiment of my invention is illustrated in the above referred to drawings, it is to be understood that they are merely for the purpose of illustration and that various changes in construction may be resorted to in the course of manufacture in order that the invention may be utilized to the best advantage according to circumstances which may arise, without in any way departing from the spirit and intention of my device, which is to be limited only in accordance with the appended claims. And while I

2

have stated the primary field of utility of my invention it remains obvious that it may be employed in any other capacity wherein it may be found applicable.

In the accompanying drawings, and in the following specification, the same reference characters are used to designate the same parts and elements throughout and in which 10 refers to the invention and 11 indicates an elongated resilient band along the upper edge 12 of which is provided a series of projecting pins 14, certain of which are integral and certain others 15 of which are detachable. The end 16 of the band is provided with a pointed tongue 17, adapted to be bent around and projected through the slot 18, adjacent the rear end 19 of the band to form a circular hoop as indicated at 21, Figure 2.

Attachable from the lower edge 21 of the said hoop are a series of spring clips 22, 23 and 24, which project below said edge 21, to form legs for the device whereby there may be a free circulation of air through the hoop. To illustrate the use of this invention, there is shown attached to the pins 14 and 15 the marginal edge 25 of a knitted mat or the like 26, for drying and which through the expansive action of the hoop will be stretched as it is dried. The ends of the hoop may be simply overlapped so as to be freely slideable whereby the expansion of the device is governed only by the resilience of the article being dried thereon. Certain of the pins 14 are fixed to the band in spaced relation to hold a certain variety of articles. However, as other articles may require more pins 15, or in particular positions, the attachable pins 15, have been provided.

As many mats are oval, an adjustable shaping member 27, which has slip jaw ends 28 and 29 for gripping opposite sides of the hoop 21, whereby they may be brought together to change the form of the device from a circle to an oval the tongue 17 or 34 being inserted in the corresponding slot 18 or 35 to prevent collapse of the hoop. The member 27 is in two sections 30 and 31, connected by a turn buckle 32, for adjustment of the band to ovals of varying arcs and dimensions.

In Figure 9 of the drawings is shown a modification in which a series of sections 33 are provided, which sections may be connected together by inserting the tongue 34 of one section through the slot 35 of another section, whereby small space will be required for packing and storing.

In Figure 10, is illustrated a still further modification in which the legs 36 are formed by W-shaped wire clips, the tongues 37 of which are

placed on one side 38, of the band and the arms 39 and 40, on the opposite side thereof. Two of members 27 may be used transversely of one another to form a square dryer, the ends of the hoop being secured as described above in connection with the formation of an oval hoop.

From the foregoing specification it will become apparent that the invention disclosed will adequately accomplish the functions for which it has been designed and in an economical manner and that its simplicity, accuracy and ease of operation is such as to provide a relatively inexpensive device considering what it will accomplish and that it will find an important place in the art to which it appertains when once placed on the market.

It is thought that persons skilled in the art to which the invention relates will be able to obtain a clear understanding of the invention after considering the description in connection with the drawings. Therefore, a more lengthy description is regarded as unnecessary.

Changes in shape, size and rearrangement of details and parts such as come within the purview of the invention claimed may be resorted to, in actual practice, if desired.

Having now described the invention that which is claimed to be new and desired to be procured by Letters Patent is:

1. The described device comprising a resilient band and a series of pins projecting from one edge thereto, certain of the pins being detachable and adjustable on the band, said band being adapted to form hoops of a variety of dimensions, means for fastening the ends of the band together, legs for the band, said legs being detachable, inflexible elongated members having slip jaw ends for gripping sides of the hoop whereby the band may be formed into ovals of varying contour, and into substantially square form.

2. The described device comprising a resilient band and a series of pins projecting from one edge thereof, certain of the pins being detachable and adjustable on the band, said band being adapted to form hoops of a variety of dimensions, means for fastening the ends of the band together, legs for the band, said legs being detachable, and inflexible elongated members having slip jaw ends for gripping sides of the hoop whereby the band may be formed into ovals of varying contour comprising rigid and extensible bars.

3. The described device comprising a resilient band and a series of pins projecting from one edge thereof, certain of the pins being detachable and adjustable on the band, said band being adapted to form hoops of a variety of dimensions, means for fastening the ends of the band together, legs for the band, said legs being detachable, and inflexible elongated members having slip jaw ends for gripping sides of the hoop

whereby the band may be formed into ovals and substantially square forms comprising a pair of extensible rods having clip ends for releasably grasping said band.

4. The described device comprising a resilient band and a series of pins projecting from one edge thereof, certain of the pins being detachable and adjustable on the band, said band being adapted to form hoops of a variety of dimensions, means for fastening the ends of the band together, and legs for the band, said legs being detachable and shiftable longitudinally of the band.

5. The described device comprising a resilient band and a series of pins projecting from one edge thereof, certain of the pins being detachable and adjustable on the band, said band being adapted to form hoops of a variety of dimensions, and means for fastening the ends of the band together comprising a transversely disposed slot on one end of the band to frictionally receive the other end of the band.

6. A doily dryer comprising a flexible band, means to secure the ends of the band together, doily-engaging pins removably securable on the upper edge of the band, and W-shaped wire legs removably securable on the lower edge of said band, the arm portions of each leg and the tongue portion of the leg frictionally engaging opposite sides of said band.

7. A doily dryer comprising a flexible band, means to secure the ends of the band together, doily-engaging pins removably securable on the upper edge of the band, and U-shaped wire legs removably securable on the lower edge of said band, the arm portions of each leg and the tongue portion of the leg frictionally engaging opposite sides of said band, said band being in a plurality of similar elongated sections, each section having a slot in one end and a tongue on the other end, the tongue of certain sections being removably inserted in the slots of adjacent sections so as to form a hoop.
